UNITED STATES PATENT OFFICE.

EMANUEL C. GIPE, OF CHICAGO, ILLINOIS, ASSIGNOR OF THREE-FOURTHS
TO FÉLIX J. GRIFFEN, OF SAME PLACE, GEORGE W. TASSELL, OF WAU-
KESHA, WISCONSIN, AND HENRY L. GLOS, OF ELMHURST, ILLINOIS.

SAFETY-LOCK FOR PACKAGE-CARRIERS.

SPECIFICATION forming part of Letters Patent No. 645,505, dated March 13, 1900.

Application filed March 2, 1899. Serial No. 707,522. (No model.)

To all whom it may concern:

Be it known that I, EMANUEL C. GIPE, of Chicago, in the county of Cook and State of Illinois, have invented certain new and useful 5 Improvements in Safety-Locks for Package-Carriers, of which the following is a full, clear, and exact description, reference being had to the accompanying drawings, forming a part of this specification, in which corresponding 10 letters of reference in the different figures indicate like parts.

In the use of package-carriers in which the usual detachable baskets are employed and connected to the car by means of an automatic locking device it frequently occurs, as a result of imperfect construction or careless usage on the part of the operator, that the basket becomes released from the car either when the impulse is given to the latter to 15 send it over the line or during its passage, when the basket, with its load, falls to the floor. Inasmuch as this frequently happens in stores crowded with customers severe personal injury, followed by damage-suits, often results, 20 to say nothing of the breakage of costly showcases and valuable goods.

The object of my invention is to overcome this difficulty by providing a supplemental safety locking device by which the basket 30 may be firmly and positively secured to the car regardless of whether the primary locking device is properly engaged or not.

I do not herein confine myself to nor claim any specific form of primary locking mechanism, inasmuch as my improved safety appliance may be satisfactorily used with any one of many well-known forms of automatic locks used for this purpose. That which I have shown and the use of which I prefer is 35 fully described and is also claimed in a pending application filed by me on the 23d day of May, 1898, as Serial No. 681,458, and therefore I shall not attempt herein to give a full and minute description of its construction or 40 operation, as I do not deem it essential to a perfect understanding of my invention.

In the drawings, Figure 1 is a side view of my improved apparatus as it would appear in use in a store, showing the suspended bas-

ket disconnected and lowered from the car. 50 Fig. 2 is a vertical sectional view in detail taken upon the line 2 2, Fig. 1, as the same would appear when the plate is attached to the basket by means of the locking mechanism of the car. Fig. 3 is a plan view of a portion of a package-carrier embodying the features of my invention. Fig. 4 is a vertical longitudinal sectional view thereof. Fig. 5 is a vertical sectional view taken upon the line 5 5, Fig. 1, viewed in the direction of the 55 arrow there shown. Fig. 6 is a like sectional view taken upon the line 6 6, Fig. 3; and Fig. 7 is a plan view in detail of the releasing-stirrup and spiral locking-studs, the latter being shown in transverse section. 60

Referring to the drawings, *a* represents the body or frame of the car, which is provided with one or more wheels *b*, adapted to run upon the usual taut wire or elevated way. A metal plate *c*, having a cross-bar *d*, is attached to the upper ends of wires *e*, from which the usual basket or goods-receptacle is suspended. A knuckle or locking device *f* (better shown in Fig. 4) is pivoted at *g*, between the two parallel bars of the frame *a*, and is provided with detents *h i j*, the former of which is adapted to be engaged and held in the position shown in Fig. 4 by means of a tooth *k* upon a pivoted spring-actuated dog *l*, adapted to be released, by means of a trigger *m*, in the manner hereinafter stated. When in said position, the bar *d*, from which the basket is suspended, is engaged and locked by means of the detent *j*, thus securing the basket to the car. 75

A stirrup *n* is arranged transversely beneath the wireway and suspended by means of chains *o o* upon opposite sides of the way, which are in turn connected with the usual lifting-cords *o' o'*, Figs. 1 and 2, by means of which the basket is raised and lowered. The springs *o² o²*, inclosed within the stationary tubes *o³ o³*, Figs. 1 and 2, serve to hold the stirrup *n* normally in the position indicated in dotted lines in Fig. 2. Notches *p p*, Figs. 1 and 4, are formed in the plate *c* for the reception of the chains *o o* when the car is at the sending-station. The lifting of the stir- 90 95

rup serves either to release the basket or to lock the same in position, according as the knuckle *f* is in one or another position when the stirrup is lifted. When the basket is locked to the car, as shown in Fig. 4, the trigger is in position to be engaged by the central depression *g* of the stirrup.

Loosely pivoted in vertical bores formed in the plate *c* upon opposite sides of a central longitudinal line drawn through said plate are studs *r r*, to the upper ends of which are rigidly attached in any well-known way buttons *s s*, having lugs *t t* upon the bottom thereof, which are adapted to engage with shoulders *u u*, formed upon the plate *c*. (Shown in Figs. 5 and 6 and indicated in dotted lines in Fig. 3.) Coiled springs *v v*, one end of each of which is connected with the plate *c* and the other with a button *s*, serve to normally hold said buttons, so that the lugs *t* are in contact with the shoulders *u*. Laterally-projecting flanges *w w*, Figs. 3, 5, and 6, are formed upon the frame of the car, and when the basket is locked to the car the buttons stand in the respective positions shown in said last-named figures with respect to said flanges.

Depending from the studs *r r* are wide spiral or auger-shaped extensions *x x*, which are adapted to enter and to be engaged by obliquely-arranged slots *y y*, formed in the stirrup *n*. The slots are so placed with reference to said extensions that when the stirrup *n* is lifted the studs *r r* are partially rotated against the action of the springs *v v*, and when the stirrup is raised to its full height the buttons *s s* stand in the respective positions indicated in dotted lines in Fig. 3, and are thus free to clear the flanges *w* as the basket is raised or lowered; but as soon as the stirrup is released said buttons resume their respective normal positions, and, assuming the release to occur when the basket is raised to its full height, so that the plate *c* is against or near to the frame *a*, the buttons will be in an engaging position above the flanges *w w*, and thus hold the basket suspended to the car, whether the main locking device is in engagement or not. The buttons *s s* should be placed sufficiently high above the flanges to enable them to assume their respective normal positions when the basket is raised without being brought into actual contact with the flanges unless the primary lock fails to engage, thus insuring a perfectly free and unobstructed movement of said buttons and providing sufficient latitude to enable them to assume positions such as will cause a positive engagement with the flanges *w* in the event of the failure of the main lock to act as stated.

Inasmuch as the springs *v* are intended merely to rotate the studs they may be made very light, and hence the auger-shaped extensions *x x* offer no appreciable resistance to the lifting of the stirrup.

While I prefer to employ two or more but-

tons upon opposite sides of the car-frame, it is obvious that one may serve the purpose without departing from the principle involved, 70 and that it may be located in any suitable position to engage the car. Moreover, it is obvious that the springs *v* may be omitted, inasmuch as the buttons *s* would be moved back and forth to the desired positions by the 75 positive action of the parts *x* and slots *y*.

Having thus described my invention, I claim—

1. The combination in a device of the class described, of a car adapted to run upon a way, 80 a detachable goods-carrying receptacle, primary and secondary automatic locks for locking the two together, one of said locks being upon the car and the other upon the suspending-plate of the goods-receptacle, and a lifting-stirrup for raising and lowering the goods-receptacle, said lifting-stirrup being adapted to engage both of said locks and to actuate the same when said stirrup is raised and lowered by the operator, substantially as described.

2. In a device of the class described, the combination of a car adapted to run upon a way, a detachable goods-carrying receptacle having a plate adapted to be engaged by a primary lock, a primary automatic lock mounted upon the car, a stirrup suspended from a cord or cords for raising and lowering said receptacle and actuating said primary lock, one or more buttons pivotally mounted upon said plate adapted to assume engaging positions with relation to the frame of said car when said plate is lifted into contact with the latter, and a depending auger-shaped extension connected with each of said buttons, said extensions being adapted to be engaged by slots in said stirrup and to be actuated thereby, substantially as described.

3. In a device of the class described, the combination of a car, a detachable goods-carrying receptacle, having a plate adapted to be engaged by a primary lock, a primary automatic lock mounted upon the car, a stirrup suspended from a cord or cords for raising and lowering said receptacle and actuating 110 said primary lock, one or more buttons pivotally mounted upon said plate adapted to assume engaging positions with relation to the frame of said car when said plate is lifted into contact with the latter, a depending auger-shaped extension connected with each of said buttons, said extensions being adapted to be engaged by slots in said stirrup and to be actuated thereby, and springs for holding 115 said buttons in normal positions respectively, 120 substantially as described.

In testimony whereof I have signed this specification, in the presence of two subscribing witnesses, this 28th day of February, 1899.

EMANUEL C. GIPE.
